UNITED STATES PATENT OFFICE

112,226

DESIGN FOR A RADIO RECEIVER CABINET

Louis J. Wronke, Chicago, Ill., assignor to Belmont Radio Corporation, a corporation of Illinois

Application October 5, 1938, Serial No. 80,280

Term of patent 7 years

To all whom it may concern:

Be it known that I, Louis J. Wronke, a citizen of the United States, residing at Chicago, in the county of Cook and State of Illinois, have invented a new, original, and ornamental Design for a Radio Receiver Cabinet, of which the following is a specification, reference being had to the accompanying drawing, forming part thereof, in which:

Figure 1 is a front elevation of a radio receiver cabinet showing my new design;

Figure 2 is a top plan view thereof; and

Figure 3 is an end elevation thereof illustrating the right-hand end of the radio receiver cabinet as viewed in Figure 1.

The characteristic features of my design are shown in solid lines in the drawing.

I claim:

The ornamental design for a radio receiver cabinet, substantially as shown and described.

LOUIS J. WRONKE.
